Primary Examiner — Susan Bennett Hattan*Assistant Examiner* — Leanne Was(74) *Attorney, Agent, or Firm* — Frommer Lawrence & Haug LLP(57) **CLAIM**

The ornamental design for a camera receiver, as shown and described.

DESCRIPTION

FIG. 1 is a bottom view of a camera receiver.

FIG. 2 is a front view of the camera receiver.

FIG. 3 is a left side view of the camera receiver.

FIG. 4 is a rear view of the camera receiver.

FIG. 5 is a top view of the camera receiver; and,

FIG. 6 is a right side view of the camera receiver.

The broken lines in the drawing depict portions of the camera receiver that form no part of the claimed design.
